UNITED STATES PATENT OFFICE.

HANS M. BOE, OF MINNEAPOLIS, MINNESOTA.

DESIGN FOR AN OIL-DISPENSING BOTTLE.

Application filed August 29, 1927. Serial No. 23,238. Term of patent 14 years.

To all whom it may concern:

Be it known that I, HANS M. BOE, a citizen of the United States, residing at Minneapolis, in the county of Hennepin and State of Minnesota, have invented a new, original, and ornamental Design for Oil-Dispensing Bottles, of which the following is a specification, reference being had to the accompanying drawing, forming part thereof.

The figure is a side elevation of the bottle, illustrating my new design.

I claim:

The ornamental design for an oil dispensing bottle, as shown.

In witness whereof, I have hereunto set my hand this 27th day of August 1927.

HANS M. BOE.
